NAPPING MACHINE

Harry Fleisher, Watertown, Conn., assignor to
Princeton, Inc., Watertown, Conn., a corpora-
tion of Connecticut

Application July 30, 1936, Serial No. 93,331

19 Claims.

(Cl. 66—147)

This invention relates to knitted fabrics, and more particularly to an attachment to a circular knitting machine for napping a tubular knitted fabric produced therein.

One object of this invention is to provide a napping device of the above nature which is provided with a plurality of napping discs which are circumferentially spaced around the tubular knitted fabric, and adapted to be rotated in opposite directions so that their flat end faces will engage the interior surface of said fabric for producing a novel circular twisted nap effect thereon.

A further object is to provide a napping device of the above nature having, in addition to the rotating napping discs, a non-rotating napping disc and a rotating napping wheel, located at spaced intervals around the periphery of the knitting machine.

A still further object is to provide a napping device of the above nature which will be simple in construction, inexpensive to manufacture, which will produce an attractive and ornamental nap on the knitted fabric, and which will be durable and efficient in use.

With these and other objects in view, there have been illustrated on the accompanying drawings two forms in which the invention may be conveniently embodied in practice.

30 In the drawings:

Fig. 1 represents a front elevation, partly in section, of a circular knitting machine upon which the improved napping mechanism has been installed.

35 Fig. 2 is a horizontal transverse sectional view of the same, the view being taken along the line 2—2 of Fig. 1, looking downwardly.

Fig. 3 is a fragmentary left side view of the rotary napping wheel positioned at the rear of the machine, as viewed in Fig. 2.

40 Fig. 4 is a fragmentary left side view of the stationary napping disc which is located at the front of the machine.

Fig. 5 is a front elevation of a modified form 45 of driving mechanism arranged to rotate the rotary napping discs in the same direction.

Referring now to the drawings in which like reference numerals denote corresponding parts throughout the several views, the numeral 10 indicates the main frame of the circular knitting machine, said frame supporting a stationary annular member 11 carrying a plurality of cams 12 which are designed to raise and lower a series of vertical knitting needles 13 disposed around a rotary cylinder 14 located within said

frame 10. A sinker bed 15 is suitably supported by brackets (not shown) above the frame 10 and carries a series of sinkers 16 for cooperating with the needles 13 in the customary manner.

In order to support the usual spool guides and other parts of the machine in an elevated position, provision is made of a pair of oppositely spaced vertical posts 17 and 18, which are detachably secured at their lower ends to the frame 10, as by nuts 18a. The upper ends of the posts 17 and 18 are attached, as by nuts 19, within a pair of tubular bosses 20, which are integrally formed at the opposite ends of an overhead cross beam 21 supported by said posts 17 and 18.

The central portion of the cross beam 21 is formed with a relatively large tubular boss 22 in which is rigidly held, as by means of a set screw 23, a large vertical support rod 24 positioned concentrically with respect to the tubular fabric produced by the knitting machine and adapted to form a support for the elevated parts of the mechanism.

As best shown in Fig. 1, the fabric 25 which is knitted by the circular row of needles 13 is drawn downwardly through the hollow interior of the rotating needle cylinder 14, and rolled up on a suitable drum at the base of the machine by suitable mechanism, not shown. As the tubular fabric 25 passes downwardly through the machine, it is held in cylindrical form by means of 30 a pair of upper and lower horizontal circular guide rings 26 and 27 which are adapted to engage the interior surface of said knitted fabric.

The upper ring 26 is preferably held stationary by means of a pair of radial flat bars 28 formed integral with a central tubular hub 29 adjustably secured on the central rod 24, as by a set screw 30, the extremities of said bars 28 being made secure to said ring 26.

The lower guide ring 27 is secured to a cross bar 31, the intermediate portion of which is apertured for loosely embracing the support rod 24. The cross bar 31 is free to rotate between a pair of rigid spaced collars 32, 33 secured to said rod 24, as by set screws 33, 33. It will thus 45 be seen that the lower guide ring 27 will be allowed to rotate with the tubular fabric within which said ring is tightly and frictionally engaged.

Napping mechanism

The napping of the tubular knitted fabric, as it passes down through the machine, is accomplished on the inner surface thereof by means of two rotating flat disc brushes 34, 35, a non-rotat-

ing flat "smoothing" disc brush 81, and an "auxiliary" rotating wheel brush 69, all of said rotary napping brushes being located substantially in a single horizontal plane midway between the guide rings 26 and 27, and said non-rotating napping brush being carried by one of the upper guide ring cross bars 28.

The pair of rotating flat disc brushes 34 and 35 are preferably provided with a multiplicity of short bristles set in square shaped blocks 36 and 37. The blocks 36 and 37 of the flat napping disc brushes 34 and 35 are seated in a pair of channel shaped holders 38 and detachably retained therein by small set screws 39. The block holders 38 are in turn attached to the outer opposite faces of a pair of small sheaves 40 and 41 loosely mounted independently of each other on the outer ends of a pair of axially adjustable non-rotating arms 42 which are threaded at their inner ends. The sheaves 40 and 41 are provided with enlarged inwardly extending hubs 43, within which are a pair of outer ball bearing raceways 44, surrounding a pair of cooperating inner raceways 44a rigidly mounted on the reduced ends 42a of the stationary arms 42. The radial arms 42 are adjustably mounted in a pair of tapped opposed tubular members 45 extending outwardly on opposite sides of the vertical support rod 24 from a hub 46 which is adapted to be held in vertically adjusted position on said rod 24 by means of a set screw 47. The tapped members 45 are adapted to receive the threaded inner ends of the arms 42.

In order to manually twist the radial shafts 42 and also serve to indicate the adjustment of the napping brushes 34 and 35, provision is made of a pair of pins 48 passing transversely through intermediate sections of said arms 42. The arms 42 are adapted to be locked securely in any desired adjusted positions by means of a pair of locking nuts 49. The axial adjustment of the radial arms 42 determines the pressure exerted by the rotating brushes 34 and 35 against the inner surface of the knitted fabric 25 to be napped.

In order to cause the fabric 25 to be held tightly against the flat working areas of the rotating disc brushes 34 and 35, provision is made of a pair of inwardly-convex elongated flat leaf springs 50, which are adapted to engage the fabric just below the brushes 34 and 35, causing said fabric to be slightly bulged inwardly, as shown in Fig. 1. The leaf springs 50 are supported at their fixed ends by flat horizontal plates 51 which are adapted to be fitted upon the lower threaded ends of a pair of vertical studs 52 (only one stud being herein shown) depending from the under surface of the knitting machine frame 10. The plates 51 are held in any desired vertical adjusted position on said studs by a pair of opposed nuts 53.

Driving mechanism

In order to continuously rotate the napping brushes to produce a twisting inclined napping action upon the interior of the traveling knitted fabric, provision is made of an elevated horizontal driving shaft 54 located above the knitting and napping mechanism and having its left-hand end journaled in an upper enlarged end 55 of an angular bracket 56, said bracket being held adjustably on the vertical rod 24, as by a set screw 57. The opposite right-hand end of the shaft 54 is journaled in another bracket (not shown), which may be readily attached to any convenient stationary part of the knitting machine. A thrust collar 58 engages the outer face of the enlarged end 55 of the bracket 56 to prevent the driving

shaft 54 from sliding to the right, as viewed in Fig. 1. The shaft 54 is driven by means of a pair of meshing beveled gears 59 and 60, the gear 60 receiving power from any suitable source, not shown.

As shown in Fig. 1, the horizontal driving shaft 54 passes directly through the axis of the vertical support rod 24, the upper part of said support rod 24 being separated by a space 61 from the lower part thereof. In order to connect the upper and lower parts of said rod 24, provision is made of a tubular sleeve 62 which is detachably locked in position thereon by means of a pair of set screws 63, 63a. A pair of transverse openings 64 are provided in the sleeve 62 for loosely accommodating the drive shaft 54 which passes therethrough.

A pair of relatively large pulley sheaves 65 and 66 are made rigid to the driving shaft 54, and are preferably equally spaced from the vertical rod 24. The sheaves 65 and 66 are connected by belts 67 and 68 with the sheaves 40 and 41, respectively, of the rotary napping brushes 34 and 35. The left-hand belt 67, as shown in Fig. 1, is crossed so that the brushes 34 and 35 will be caused to rotate in opposite directions, and thereby produce a more effective twisting napping upon the fabric 25 as the latter moves downwardly and rotates past said brushes in a helical manner.

In order to produce a vertical napping of the fabric 25 in addition to the rotary napping produced by the brushes 34 and 35, provision is made of a thin brush 69 having a cylindrical napping surface and rotating in a vertical plane, said brush 69 being hereinafter referred to as the "auxiliary" brush. As best shown in Fig. 2, this auxiliary brush 69 is mounted on a horizontal stub spindle 70 rigidly secured to a hollow hub 71, the latter having an integral sheave 72 and being mounted by means of ball bearings 73 upon a stationary axle 74 projecting from the outer face of an angular bracket 74a. The angular bracket is adjustably supported on the outer threaded end of a horizontal support bar 75 and is retained in adjusted position thereon by a pair of opposed locking nuts 76, 76. The opposite end of the support bar 75 is threadededly engaged in an apertured rectangular block 77 adjustably fitted over the right-hand member 45 of the hub 46 and locked in position, as by a set screw 78.

The auxiliary wheel brush 69 is driven by means of a belt 79 engaging the sheave 72, similar to the sheaves 40 and 41 and passing over a large sheave 80 (similar to sheaves 65 and 66) rigid on the driving shaft 54 and located adjacent the sleeve 62 of the support rod 24. As shown in Fig. 3, the auxiliary brush 69 is adapted to rotate in such a direction as to cause its peripheral surface to travel downwardly rapidly in the same direction as the slow movement of the knitted fabric 25. It is within the spirit and scope of the present invention, however, to rotate the auxiliary wheel in the opposite direction if desired.

Smoothing-out brush

The stationary disc brush 81 is attached to the downwardly offset end 82 of a strap bracket 83 secured to the underside of the cross bar 28 by means of a pair of bolts 84, 84. The offset end 82 extends downwardly to a position where the attached brush 81 will engage the fabric 25 just below the working plane of the rotary brushes 34 and 35 and the auxiliary brush 69, and serves to smooth out the nap raised on the fabric by said rotary brushes. The strap bracket 75

83 is provided with an elongated slot 85 through which the bolts 84 pass, which construction permits adjustment of said bracket 83 with respect to said cross bar 28, whereby the smoothing brush 81 may be held against the fabric 25 with any desired pressure.

Modified form of napping device

In case it is desired to rotate the disc napping brushes in the same direction by employing only a single belt, the form of the invention shown in Fig. 5 may be employed. In this form, the main support rod 24' will be also separated at a point 86 between the napping brush discs, and the adjacent ends of said rod 24' will be joined by a hollow T-member 87 having a vertical sleeve 87a and set screws 88 passing therethrough into engagement with the adjacent ends of said rod. The T-member 87 is also provided with horizontal opposed tubular sleeves 89 terminating in enlarged ends 90. In this form of the invention, a horizontal spindle shaft 91 passes through the space 86 and fits loosely within the horizontal sleeves 89. The outer ends of said shaft 91 are journaled in ball bearing mountings 92, 92 carried by the enlarged ends 90, 90 of said hollow T-member 87.

The outer ends of the horizontal shaft 91 are threaded and adapted to adjustably receive a pair of tapped hubs 93, 93 formed integral with a pair of channel blocks 94, 94, which are adapted to detachably hold the brushes 34' and 35'. A pair of locking nuts 95 are provided for securing the hubs 93, 93 in adjusted positions upon the opposite ends of the spindle 91. The spindle shaft 91 is adapted to be rotated by means of a single sheave 96 secured to said shaft 91 and driven by a belt 97 which in turn passes over a large sheave (not shown) keyed to the elevated driving shaft 54.

While there have been disclosed in this specification two forms in which the invention may be embodied, it is to be understood that these forms are shown for the purpose of illustration only, and that the invention is not to be limited to the specific disclosures but may be modified and embodied in various other forms without departing from its spirit. In short, the invention includes all the modifications and embodiments 50 coming within the scope of the following claims.

Having thus fully described the invention, what is claimed as new, and for which it is desired to secure Letters Patent, is:

1. In a combined knitting and napping machine, mechanism for knitting a tubular fabric, means for interiorly supporting said fabric at a pair of spaced circumferential lines, and interior rotating flat-faced napping disc located between said supporting means, and means for causing the flat face of said disc to contact with said fabric.

2. In a napping machine, means for interiorly supporting a tubular fabric along a pair of spaced lines, an interior rotating flat-faced napping disc with an outwardly extending napping surface on its flat face located between said supporting means, and means to cause the flat face of said disc to engage and nap the interior surface of said fabric.

3. In an apparatus for napping the interior surface of a continuously traveling tubular knitted fabric, a rotating flat-ended member having napping means on its flat end surface, and resilient means pressing inwardly upon said fabric to

cause said member to engage the interior surface of said tubular fabric along a flat area thereof.

4. In a napping apparatus, means for continuously delivering a slowly rotating tubular knitted fabric, a rotating napping member having a flat face located within the circular path of said tubular fabric, and means on the exterior of said fabric to resiliently press upon a portion of said fabric to cause a flat area of said fabric to contact with the flat napping face of said member.

5. In an apparatus for napping the interior surface of a continuously traveling tubular knitted fabric, a pair of rotating members having flat napping end faces, and resilient means pressing inwardly upon said fabric to cause the napping faces of said members to engage the interior surface of said tubular fabric along a pair of separated flat areas thereof.

6. In an apparatus for napping the interior surface of a continuously traveling tubular knitted fabric, a plurality of rotating members having flat napping end surfaces located within said fabric, and resilient inwardly pressing exterior means for pressing corresponding flat areas of the interior surface of said fabric against said rotating members to produce an inclined napped effect thereon.

7. In an apparatus for napping the interior surface of a continuously traveling tubular knitted fabric, a pair of rotating members having flat napping end faces, and resilient means outside said fabric to cause the napping faces of said members to engage the interior surface of said tubular fabric along a pair of separated flat areas thereof, and means to rotate said discs in opposite directions.

8. In an apparatus for napping the interior surface of a continuously traveling tubular knitted fabric, a pair of rotating members having flat napping end faces, exterior means pressing inwardly upon said fabric to cause the napping faces of said members to engage the interior surface of said tubular fabric along a pair of separated flat areas thereof and produce an inclined napping effect, and a non-rotating napping member spaced from said rotating members for smoothly brushing the napped surface of said fabric.

9. In an apparatus for napping the interior surface of a continuously traveling tubular knitted fabric, a pair of rotating brushes having flat napping end faces, exterior means inwardly pressing on said fabric to cause the napping faces of said brushes to engage the interior surface of said tubular fabric along a pair of separated flat areas thereof, and a rotating auxiliary brushing wheel having a thin cylindrical napping periphery for napping the interior surface of said fabric along a line located between said flat areas.

10. In an apparatus for napping the interior surface of a continuously traveling tubular knitted fabric, a pair of rotating brushes having flat napping end faces, exterior means pressing inwardly on said fabric to cause the napping faces of said brushes to engage the interior surface of said tubular fabric along a pair of separated flat areas thereof, and a rotating auxiliary brushing wheel having a cylindrical napping periphery for napping the interior surface of said fabric along a line located between said flat areas.

11. In an apparatus for napping the interior surface of a tubular knitted fabric which is continuously moved longitudinally and slowly rotated at the same time, means to force said fabric inwardly, a rotating member inside said fabric hav-

ing a flat end napping surface for engaging and napping a flat area of said fabric, and a non-rotating brush inside said fabric spaced from said rotary napping member.

5 12. In an apparatus for napping a continuously helically moving tubular knitted fabric, a rotating flat surfaced napping member engaging and napping said fabric along a flat area thereof, means for forcing said fabric against the flat 10 surface of said napping member, and a non-rotary napping member spaced longitudinally from said rotating napping member for smoothly brushing the surface of said fabric.

15 13. In an apparatus for napping a tubular knitted fabric which is continuously rotatable and movable in a longitudinal direction, a central vertical supporting bar, a horizontal driving shaft passing through said bar, a pair of interior fabric supporting rings below said shaft, a pair of 20 napping members mounted to rotate on horizontal axes between said rings, means to press said fabric inwardly against said napping members, said members having outer flat surfaces adapted to nap the interior surface of said fabric along 25 a pair of flat areas, and means operated by said shaft for continuously rotating both of said members.

30 14. In an apparatus for napping a tubular knitted fabric which is continuously rotatable and movable in a longitudinal direction, a central vertical supporting bar, a horizontal driving shaft passing through said bar, a pair of interior fabric supporting rings below said shaft, a pair of 35 napping members mounted to rotate on horizontal axes between said rings, means to press said fabric inwardly against said napping members, said members having outer flat surfaces adapted to nap the interior surface of said fabric along a pair of flat areas, and means operated by said 40 shaft for continuously rotating both of said members, said upper supporting ring being stationary, and said lower supporting ring being rotatable on said central bar with said fabric.

45 15. In an apparatus for napping the interior surface of a longitudinally traveling tubular knitted fabric, a central supporting bar, a rotating brush having a flat end napping surface for engaging a flat area of said fabric, and an aux-

iliary napping wheel having a cylindrical napping periphery adapted to engage a vertical line of said fabric, said brush and wheel being mounted to rotate in bearings supported by said central bar, and means to press said fabric inwardly 5 against said brush and napping wheel.

16. In an apparatus for napping the interior surface of a longitudinally traveling tubular knitted fabric, a vertical central supporting bar, a horizontal driving shaft, a rotating brush journaled 10 on a horizontal axis and having a flat end napping surface, and an auxiliary napping wheel having a cylindrical napping periphery adapted to rotate in the direction of movement of said fabric, and belt and pulley means connecting said driving shaft with said brush and said napping wheel to rotate the same.

15 17. In an apparatus for napping the interior surface of a continuously traveling tubular knitted fabric, a rotating flat-ended member having napping means on its flat end surface, means to press said fabric against said member to engage the interior surface of said tubular fabric along a flat area thereof, and means for adjusting the pressure of said napping member against said fabric. 20

25 18. In an apparatus for napping the interior surface of a tubular knitted fabric which is continuously moved longitudinally and slowly rotated at the same time, means to press said fabric inwardly, a twisting member having a flat end 30 napping surface for engaging and napping a flat area of said fabric, a non-twisting brush spaced vertically from said rotary napping member, and means to adjust the pressure of said non-twisting brush upon said fabric.

35 19. In an apparatus for napping the interior surface of a longitudinally traveling tubular knitted fabric, a central supporting bar, means to press said fabric inwardly, a rotating brush having a flat end napping surface for engaging a 40 flat area of said fabric, and an auxiliary napping wheel within said fabric having a cylindrical napping periphery adapted to engage a vertical line of said fabric, said brush and wheel being mounted to rotate in bearings supported by said central bar, and means to adjust the pressure of said auxiliary napping wheel.

HARRY FLEISHER.
